PIANO DESK

Filed Feb. 28, 1927

UNITED STATES PATENT OFFICE.

GEORGE WILSON MacDOW, OF WATERTOWN, MASSACHUSETTS, ASSIGNOR TO HENRY F. MILLER PIANO COMPANY, OF BOSTON, MASSACHUSETTS, A CORPORATION OF MASSACHUSETTS.

PIANO DESK.

Application filed February 28, 1927. Serial No. 171,444.

This invention relates to improvements in piano desks. More especially it relates to a movable piano desk, having an adjustable music rack associated therewith, which affords protection at all times for the portion of the piano below it.

So far as I am aware, the movable piano desks heretofore used have been so constructed that when the rack or easel is raised 10 in position to support the music there is no protection against dust or other foreign matter that may fall onto the wires and piano mechanism. Inasmuch as most people desire to have their pianos open the greater part of 15 the time whether being actually played or not, the gradual accumulation of dust and the like becomes a serious menace both to the proper functioning of the mechanical parts and to the tone quality of the instrument. The present invention is directed to the elimination of such a menace.

It is among the objects of this invention to provide a piano desk which will always serve as a cover for the front portion of the 25 piano over which it is placed. It is a feature of the construction that this desk may be moved inward or outward to vary the distance of the music from the eyes of the player, and that the rack which is associated 30 therewith may be set at different angles of inclination when supporting the music and may be housed within a space in the desk when the piano cover is to be closed.

In a preferred embodiment of the invention 35 the desk comprises a pair of end members having grooved edges for engaging rails on the inner sides of the piano case, and having bars connecting their adjacent front and rear corners. Along the inner lower edges 40 of these end members and bars is attached a cover board that fills the space defined by them. In the recess above this cover board the music rack, together with its brace, can be closed down below the level of the end 45 members. When raised, the brace engages suitably notched side pieces and thus holds the rack at an inclination. This raising of the rack, however, does not expose the portion of the piano below the desk, because 50 the cover board still remains to protect whatever is underneath. The desk is proportioned so that when forward with its front edge nearly over the rear of the key board, the back of the desk is still under the cover

or lid of the piano. Thus the desk at all 55 times will serve as a protection for the pins, action and forward portions of the wires which have heretofore been exposed.

It is intended that the patent shall cover, by suitable expression in the appended 60 claims, whatever features of patentable novelty exist in the invention disclosed.

In the accompanying drawings:

Figure 1 is a plan view of a piano embodying the desk of the invention, showing the 65 rack down;

Figure 2 is a plan of the improved desk alone showing the rack up;

Figure 3 is an end view of an end member 70 of the desk; and

Figure 4 is an elevation, in section on line 4-4 of Figure 1, showing a portion of the piano protected by the improved desk.

Referring more particularly to the drawings a piano case 10 has a cover 12 with forward section 12^a foldable back upon the rear section as shown. The piano desk 14 is supported movably on rails 16 which are fastened to the sides 10^a of the case and enter grooves 18 in the end members 20. Between 75 the latter along the front and back edges of the desk are bars 22 which are joined to the end members by cleats 24. The music rack 26 is hinged to the front bar 22^a and can be adjusted at different angles with the 80 horizontal by means of a brace whose legs 28 are hinged to the back of the rack and whose cross member 28^a engages notches 30 in side pieces 32 close by the inner edges 85 of the end members. When not supported 90 uprightly by its brace the rack can be turned down and laid between the end members 20 and the bars 22 in a space surrounded by them. When thus down, the rack and end members together would serve as a cover 95 for the portion of the piano below, but ordinarily when the rack is down the lid is turned forward and the piano as a whole is closed.

It is when the lid is back and the rack is 100 up that the danger from falling dirt is present, and to eliminate this the present invention provides a cover board 34, which fits tightly between the end members 20 and bars 22, whose lower inner edges are undercut to receive it. This board 34 makes of 105 the piano desk a solid cover, as it were, which effectually protects the wire pins 36,

the front ends of the wires 38, the mute pieces 40, and all the action A which is below the space occupied by the desk. Preferably the desk is made deep enough, in the rearward direction, so that when pulled as far forward as one would wish its rear edge is still under the lid 12, as shown in Figure 4. Thus the movable desk, having an adjustable music rack which can be lifted up, is withal a protection for the portion of the piano below it, preventing dust, torn pieces of music or other things from dropping onto the action or accumulating on the wires. As a consequence the mechanism is not interfered with and the original tone of the instrument is not disturbed as heretofore by a collection of foreign matter.

I claim as my invention:

1. A piano desk adapted to be moved inward and outward in a piano case and comprising a music rack which can be raised from the plane of the desk to an angle therewith and a cover board underlying the rack when down and covering that portion of the piano below, which would be exposed when the rack is raised.
2. A piano desk for a piano comprising end members adapted to engage the sides of the case to permit inward and outward movement of the desk; bars connecting the front and back edges of said end members; a board fastened to said members and bars and covering the space defined by them; and a music rack, overlying said cover board when

down, and adapted to be adjusted in an upright position at an inclination to said cover board.

3. A piano desk for a piano having a lid that can be folded backward comprising means at the ends of said desk for engaging the case to permit inward and outward movement of the desk and a rack which can be raised from the plane of the desk to an inclination therewith; the said desk having an uninterrupted closed surface throughout its extent and being so proportioned that when moved forward said surface extends rearward under the piano lid.

4. A piano desk adapted to form a cover for the portion of the piano below it, comprising a pair of end members engaging the sides of the desk movably, and a cover board immovably connected to said end members and forming therewith a continuous unopen surface.

5. A piano desk adapted to form a cover for the portion of the piano below it, comprising a closure member extending across the piano case from one side to side and means mounting it thereon to permit inward and outward movement of the desk; a recess in the upper side of said desk; and a music rack adapted when down to rest in said recess and provided with means for holding it raised at an inclination to the closure member of said desk.

GEORGE WILSON MacDOW.
